UNITED STATES PATENT OFFICE.

ARTHUR T. KUEHNER, OF ELKRIDGE, MARYLAND.

LOCOMOTIVE DRIVING BOX.

1,425,493.

Specification of Letters Patent.

Patented Aug. 8, 1922.

Application filed July 17, 1920. Serial No. 397,000.

To all whom it may concern:

Be it known that I, ARTHUR T. KUEHNER, citizen of the United States, residing at Elkridge, in the county of Howard and State 5 of Maryland, have invented certain new and useful Improvements in Locomotive Driving Boxes, of which the following is a specification.

This invention relates to an improved 10 locomotive driving box of the general type disclosed in my pending application for a similar invention filed November 20, 1919, Serial No. 339,347, and has as one of its principal objects to provide a driving box 15 employing a removable face plate so that the box may, without displacing the locomotive drive wheels, be dismounted and wherein the face plate may be removed with a minimum of difficulty.

20 The invention has as a further object to provide a driving box wherein the face plate will be formed of companion sections which may simply be displaced laterally in a plane parallel to the outer face of the box 25 body.

A still further object of the invention is to provide a driving box wherein the sections 30 of the face plate will be securely locked to the box body and wherein the weight of the load will be utilized for holding said sections 35 against upward movement.

And the invention has as a still further object to provide a driving box wherein the face plate will be so formed as to present 40 a continuous wearing surface to the wheel hub.

Other and incidental objects will appear hereinafter.

In the drawings:

45 Figure 1 is an elevation looking at the outer side of my improved driving box,

Figure 2 is a fragmentary vertical section, parts being shown in elevation,

Figure 3 is a perspective view showing the 50 sections of the face plate of the box in detail,

Figure 4 is a plan view of the face plate.

Figure 5 is a transverse section on the line 55 5—5 of Figure 1, looking in the direction of the arrows, and

Figure 6 is a detail perspective view showing the head of one of the securing bolts for the face plate.

In carrying the invention into effect, I 60 employ a box body 10 provided at its inner side with vertical flanges 11. The box body

is recessed in the usual manner to receive a wheel axle as conventionally illustrated at 12 and in the drawings I have indicated the driving wheel at the adjacent end of this 60 axle at 13. Projecting from the outer side of the box body is an arcuate flange 14 and seated within the box body to extend beneath said flange is a crown brass 15 journaling the axle 12. Projecting from the legs of the 65 box at its outer side are lugs 16 arranged adjacent the lower ends of said legs to depend therebeneath and provided at their upper ends with inwardly and downwardly sloping concave shoulders 17 tilted in the direction of the journal receiving recess in the 70 box body. Depending from the legs of the box at its inner side are lugs 18 and fitting between the lower end portions of the legs is a shelf 19 having lugs 20 mating with the 75 lugs 16 and 18. Engaging through all of the lugs at the inner side of the box is a bolt 21 and engaging through the pairs of lugs at the outer side of the box are bolts 22. As will be perceived, the bolts 21 and 22 will 80 thus serve to rigidly secure the shelf in position so that the shelf will act to tie the legs of the box together and brace the legs with respect to each other. Rested upon said shelf between the box legs is a grease cellar 85 23 provided at its inner end with lugs through which are engaged stub bolts threaded into the box body and removably securing the cellar in place.

Overlying the outer side of the box is a 90 face plate which is formed of companion semi-circular sections 24 fitting the flange 14 and meeting at their ends medially of the box body. Formed on these sections are vertical flanges 25 overhanging the box body 95 at the outer side thereof and adapted to co-operate with the flanges 11 for receiving the legs of a pedestal. At the upper ends of the flanges 25 are provided openings 26 in which a suitable tool may be engaged for removing 100 the sections. Upstanding from the sections at their upper ends are confronting lugs 27 and engaging through these lugs is a tie bolt 28 rigidly connecting the sections. Formed on the lower end portions of the sections at 105 the confronting side edges of the flanges 25 are downwardly and inwardly sloping convex shoulders 29 which fit the shoulders 17 of the box body. These shoulders will thus coact for not only securing the lower ends 110 of the sections of the face plate against outward movement but will also coact for rigidly

securing the lower end portions of the face plate against spreading. Freely fitted through the upper end portion of the box body near its upper corners are bolts 30 provided at their outer ends with flat heads 31 and, as particularly shown in Figure 6, the heads of these bolts are formed with oppositely sloping inner end edges providing at the inner end of each bolt head reversely presented shoulders 32. The sections of the face plate are provided in the outer sides thereof with cylindrical recesses 33 for freely receiving the bolt heads 31 and entering these recesses are slots 34 through which the bolt heads may be projected. Further, the box body 10 is provided at its outer side with recesses 35 into which the bolt heads may be retracted so as to lie flush with the outer side face of the box body. Thus, it will be seen that by retracting the bolts 30 so that the heads thereof will be disposed within the recesses 35, the sections of the face plate may be applied and the shoulders 29 thereof engaged with the shoulders 17 of the lugs 16. The bolts may then be shifted outwardly to project the bolt heads 31 through the slots 34 of the sections of the face plate into the recesses 33, when by rotating the bolts a half turn the bolt heads 30 will be disposed to coact with the bottom walls of the recesses 33 so that the nuts upon the bolts may be tightened for firmly binding the sections of the face plate against the box body. In this connection, it is to be noted that the shoulders 32 of the bolt heads will, when the nuts upon the bolts 30 are rotated, coact with the bottom walls of said recesses for holding the bolts against rotation so that said nuts may be readily tightened or as easily removed.

Beyond the flanges 25, the lower end portions of the sections 24 are provided with reduced arcuate extensions 36, these extensions being thus reduced so as to accommodate the outer end portion of the cellar 23 in the rear thereof and, as particularly shown in Figure 5, said extensions are formed with mating beveled edges so that the ends of the extensions are thus overlapped. Overlying the extensions and continuing over the outer faces of the sections of the face plate are the substantially semi-circular portions of an annular hub bearing 37. This bearing is seated in a suitable dove-tailed channel in the outer faces of the sections and, as will be observed, the bearing provides a continuous bearing surface for a wheel hub at the outer side of the box. Formed in the upper end of the box body near its inner side is a recess 38 and formed in the upper end of the box body to open through the outer side thereof is a recess 39. Mating with this recess 39 are recesses 40 in the upper ends of the sections of the face plate. The recess 38 is designed to receive one leg 41 of a spring

saddle while the mating recesses 39 and 40 are designed to receive the other leg 42 of said saddle. The legs of the spring saddle have been conventionally shown. Thus, as will be seen, the leg 42 will rest partially upon the box body and partially upon the upper ends of the sections of the face plate so that the weight of the load will be utilized for holding these sections against upward movement. The bolts 30 will consequently be relieved of excessive upward stress.

As will now be readily understood in view of the preceding description, the lower ends of the sections of the face plate will be locked to the box body by the coacting shoulders 17 and 29 and will also be locked against spreading by said shoulders. Similarly, the upper ends of the sections of the face plate will be locked to the box body by the bolts 30 while these bolts in conjunction with the tie bolt 28 will serve to lock the upper ends of the sections against spreading. The bolts will also serve to resist upward thrust against the sections of the face plate and such upward thrust will also be resisted by the load upon the spring saddle. The sections of the face plate will thus be effectually maintained in position. However, to remove the face plate, it is simply necessary to relieve the spring saddle of the load thereon when, by removing the tie bolt 28 and retracting the heads 31 of the bolts 31 into the recesses 35 of the box body, the sections of the face plate may simply be shifted laterally and thus displaced, it being noted that the sections of the face plate may be thus moved laterally in a plane parallel to the plane of the outer face of the box body. The face plate may thus be displaced with a minimum of difficulty and when so displaced the box body may, of course, be shifted inwardly through the pedestal and itself displaced.

Having thus described the invention, what is claimed as new is:

1. A journal box including a box body, a face plate secured to the outer side of the box body and providing a continuous annular hub bearing, and means extending through the box body connecting the face plate therewith and retractable to permit removal of the face plate in a plane parallel to the adjacent face of the box body.
2. In a journal box, the combination of a box body having flanges thereon, a sectional face plate seating against the outer side of and overhanging the box body to provide flanges disposed to cooperate with said first mentioned flanges for operatively receiving a pedestal for the box, and means connecting the plate sections with the box body and retractable to permit lateral removal of said sections in a plane parallel to the adjacent face of the box body.
3. In a journal box, the combination of a

110

125

130

box body, a face plate seating against the outer side thereof, the face plate being formed of sections, and means extending through the box body to coact with said sections individually for securing the sections in position and retractable to permit lateral removal of the sections in a plane parallel to the adjacent face of the box body.

4. In a journal box, the combination of a box body, a face plate seating against the outer side thereof, the face plate being formed of companion sections coacting at their lower ends to provide a lapped joint therebetween, and means extending through the box body connecting the face plate therewith and retractable to permit lateral removal of said sections in a plane parallel to the adjacent face of the box body.

5. In a journal box, the combination of a box body, a face plate seating against the outer side thereof, the face plate being formed of sections having laterally directed

extensions thereon meeting to provide an annular hub bearing, and means connecting the sections with the box body, the extensions being reduced in thickness to accommodate the outer end of a grease cellar fitting between the legs of the box body.

6. In a journal box, the combination of a box body having pedestal flanges, a face plate seating against the outer side of and overhanging the box body providing pedestal flanges to cooperate with said first mentioned flanges, the face plate being formed of sections having laterally directed extensions thereon extending toward each other in a direction between the legs of the box body to provide an annular hub bearing, and a grease cellar disposed between the legs of the box body supporting said extensions against inward lateral thrust.

In testimony whereof I affix my signature.

ARTHUR T. KUEHNER. [L.S.]
